UNITED STATES PATENT OFFICE.

DOLPHUS TORREY, OF NEW YORK, N. Y.

CAR-BRAKE.

SPECIFICATION forming part of Letters Patent No. 276,934, dated May 1, 1883.

Application filed November 20, 1882. (No model.)

To all whom it may concern:

Be it known that I, DOLPHUS TORREY, of the city, county, and State of New York, have invented an Improvement in Emergency-Brakes for Railway-Cars, of which the following is a specification.

My invention relates to a brake apparatus intended to secure the application of the brakes upon cars which may be accidentally detached from the train, as by the breaking of the coupling-link between the cars. To this end I connect the brake rod or chain of one car with the car immediately in front through the medium of a separable clutch. In one embodiment of the invention the clutch is inclosed in a sleeve or open-ended box or socket fixed to the car to which the brakes are applied, the extremity of the clutch-connection being hooked to the preceding car and the parts so constructed and combined that on the severance of the car-coupling the clutch-connection will, by the separation of the cars be drawn through the fixed sleeve, so as to apply the brakes and at the same time permit the separation of the clutch, one member of which is carried away by the forward car, while the other member is caught by the forward end of the sleeve, so as to retain the brakes in their strained condition. Under another embodiment of the invention an ordinary hand - staff or windlass forms the means of attachment for the chain connecting with the preceding car, the connecting or emergency chain, which is attached to the preceding car, being so coiled on the hand-brake staff or windlass as to rotate the same and draw on the brakes when the preceding car moves away. The emergency-chain then escapes from the windlass, and the latter is caught by its pawl or ratchet, so as to hold the brakes "on."

In the accompanying drawings, Figure 1 is a side elevation of adjacent parts of two connected cars, showing the application of the invention. Fig. 2 is an end view, on a larger scale, of a fixed box or sleeve within which the automatic-brake appliance works. Fig. 3 is a longitudinal section of the apparatus, also on a larger scale. Fig. 4 is a longitudinal section showing the apparatus in action, as on the accidental breakage of a car-coupling. Fig. 5 is a longitudinal section of a clutch of modified form. Fig. 6 is an elevation illustrating another modification, in which the clutch or

connection consists of an emergency - chain connected with the preceding car and coiled on a hand-brake staff or windlass, so as to wind up the brakes when drawn off.

The fixed sleeve or box 1, Figs. 1 to 5, inclusive, may consist of a rectangular tube one foot in length, one by three inches in diameter, and open at both ends. At its rear end is an inturned lug, 9, to prevent the clutch or coupling-piece pulling out backward. One of the boxes 1 is fixed to the bed-frame of the car or at or near each end, and contains a clutch consisting of two members, 2 3, which are held in lock or engagement by the said fixed sleeve 1. The fixed sleeve also confines a spring, 4, the expansion of which, on escaping from the sleeve, permits or causes the disengagement of the clutch members 2 3. The clutch-piece 2 is attached to a pull-chain, 5, connected with a lever, 11, of the brake system of the car to which the sleeve 1 is fixed. The other clutch-piece, 3, is attached to the emergency-chain 6, terminating in a ring, 7, which, when at the rear end of the car or out of use, may be caught on a hook at the end of its own car. The ring 7 of the emergency-chain 6 at the forward end of each car is, on making up the train, dropped over the head of the coupling or any other pin on the car ahead. The engaging faces of the clutch members 2 3 are shown at 10 10. The clutch-piece 2 is further provided with a shoulder, 8, which, in the normal position of the apparatus, engages with the internal lug, 9, at the rear end of the fixed sleeve 1, preventing the escape of the clutch backward and affording a bearing or fulcrum-point at either end of the car to permit the straining of the brakes from the other end.

It will now be apparent that in the event of the breaking of a coupling the forward car, in separating from that behind it, will draw the clutch 2 3 through the fixed sleeve 1. As it emerges therefrom the spring 4 expands, releasing the member 3 from the piece 2, and at the same time throws the shoulder 8 into engagement with the forward end of the sleeve, so as to hold the brakes in the strained condition to which they are drawn, while the emergency-chain goes with the forward car without any breakage of the apparatus or violence thereto.

In the embodiment of the invention repre-

sented in Fig. 5 the clutch member 2 consists of two pieces hinged together and confining the arrow-headed piece 3 between them while within the sleeve and expanded by the spring 4, so as to release the piece 3 and cause the two shoulders 8 to engage the front of the sleeve when drawn out. I have used both forms of the device in practice with good effect.

A simple mode of applying my invention of an emergency-brake in connection with an ordinary hand-brake staff or windlass is illustrated in Fig. 6. The emergency-chain 6 is here coiled on the hand-shaft or windlass 12, so as in being drawn off to wind the ordinary brake-chain thereon. The shaft, being then caught by the spring-ratchet 13, holds the brakes on while the chain 6 is pulled off the pin 14, on which it was caught on said shaft, and escapes without damage. In either case the brakes are instantly applied to the forward car of an accidentally-uncoupled section of a train, and the checking of the speed of this forward car may cause an automatic application of the brakes to the following cars by a customary momentum-brake apparatus. In case it is desired that the brakes shall be applied to the last car in front of a severed coupling, the emergency-chain 6 may be connected with a like chain upon the preceding car, instead of to a pin thereon, and so secure an automatic application of the emergency-brakes to the two cars in case of an accidental severance of the train.

Having thus described my invention, what I claim is—

1. A separable coupling for railway-brake systems, consisting of two members provided with means for effecting their engagement with each other, and a fixed sleeve or other containing device, within which the coupling members are held in engagement, one of said members being provided with an attachment for effecting its connection with the brake mechanism of the car upon which it is placed, and the other member being provided with an attachment for effecting its connection with a car adjacent to the first-mentioned car.

2. In a separable coupling for railway-brake systems, the combination, with a sleeve or other similar device provided with stops or lugs, substantially as described, of a separable clutch composed of two members arranged to engage with each other, one of said members being connected with the brake mechanism and provided with a device for engaging with the stops of the sleeve, and also with a spring for insuring such engagement, and the other member being connected with the car adjacent to that carrying the sleeve.

3. The combination of the clutch or coupling 6 and spring 4 and fixed sleeve 1, substantially as and for the purpose set forth.

4. The combination of the chains or rods 5 and 6 with the couplings 2 and 3, substantially as and for the purposes set forth.

DOLPHUS TORREY.
